ATTORNEY

UNITED STATES PATENT OFFICE.

CONRAD R. BUCHET, OF LONG BEACH, CALIFORNIA.

TOY SPEED BOAT.

Application filed April 2, 1927. Serial No. 180,537.

This invention relates to toy boats especially adapted to be used on the shallow lakes and streams in amusement and recreation parks, and occupied and guided by children in the 5 pursuit of pleasure and is designed to be provided with a suitable steering gear and a propeller driven by an electric motor installed in the boat.

The main object of the invention resides in 10 the efficient and novel manner of the mounting of the motor and the propeller shaft which extends outwardly through the bottom of the boat in such manner that the water will not work into the motor and damage same.

15 Another object of the invention is to provide a novel flexible means for coupling the propeller shaft to the motor shaft.

The above and other objects of the invention will be more fully described in the following specification and exemplified in the 20 accompanying drawings, in which:

Figure 1 represents a longitudinal section through a boat embodying the features of the invention.

25 Figure 2 is an enlarged longitudinal section through a portion of the shaft mounting illustrating the flexible coupling between the motor shaft and the propeller shaft.

Figure 3 is a transverse section through the 30 same taken on the line 3—3 of Figure 2.

In carrying out the invention, 5 represents a boat which may be of any desired model and formed of any desired material and is provided with a front seat 6 and a rear seat 7.

35 The steering apparatus is shown in a conventional manner and comprises a rudder 8 which is located at the stern of the boat and is provided with a stem or shaft 9 which is journaled in a bearing 10 secured to the bottom 40 of the boat. A lever 11 is secured to the top of stem 9, which extends into the boat, and pivoted to the end of said lever is one end of a rod 12. The other end of the rod 12 extends forwardly and is pivoted to a crank 45 13 which is secured to a shaft 14, journaled in a bearing 15 secured to the boat and secured to the upper end of said shaft is a steering wheel 16 which is located adjacent the seat 6 upon which the navigator sits.

50 Mounted in the bottom of the boat is a standard 17 which is provided with a flange 18 resting on the boat's bottom and secured thereto in any suitable manner as by means of the bolts or lag screws 19.

55 The standard 17 comprises a casing in the shape of a hollow sleeve 20 at its forward end

and a hollow stem 21 to its rearward end, both of which are inclined downwardly as they extend rearwardly, the stem passing outwardly into the water through an aperture 60 22 in the bottom of the boat, and in order that water may not leak through said aperture, a suitable packing gasket 23 is interposed between the flange 18 and the boat's bottom as shown in Figure 1 of the drawings. 65

Secured to the forward end of the casing 20 is an electric motor 24 which is also inclined in the same manner as the casing, and is adapted to be operated in the usual manner by a storage battery, not shown, located in the 70 boat.

The motor shaft 25 projects into the casing 20, and has secured to its end a flexible sleeve 26 by means of a cotter pin 27, and is preferably composed of canvas and rubber, similar 75 to that of a hose.

Socketed into the opposite end of sleeve 26 is one end of the propeller shaft 28 which is secured thereto by means of the cotter pin 29.

The shaft 28 is journaled in suitable bearings in the stem 21 and is incased thereby and has secured to its rear end the propeller 30.

The boat is provided with the usual false bottom 31 under which is located all of the 85 working parts with the exception of the motor which is located under the front seat 6 as shown.

By the above recited construction it will be 90 obvious that no expensive and frictional resisting packing will be necessary at the rear end of shaft 28, due to the incline of same, which prevents the water from reaching the motor as the motor is located above the water line as indicated at the line a—a, and that an 95 efficient and economical flexible coupling has been provided to form the juncture between the motor and propeller shaft as shown in Figure 2, the relatively thick, flexible sleeve 26 normally maintains the adjacent shaft ends 100 slightly spaced apart thus providing for neutralizing vibration resulting from rapid propulsion of the propeller and yet transmitting power in a smooth, dependable manner.

Having thus described my invention what 105 I claim is,

1. In a toy boat; a casing secured in said boat extending downwardly and rearwardly and passing through an aperture through the bottom of said boat, a propeller shaft journaled in said casing having secured to its rear end a propeller; a motor secured to the 110

forward end of said casing and having the rear end of its shaft extending into said casing adjacent the forward end of the propeller shaft, and a flexible coupling member 5 consisting of a non-metallic sleeve located in said casing and detachably secured to the ends of said shafts.

2. In a toy boat, the combination, with a motor and a propeller to be driven by said 10 motor; of a shaft operatively connecting said motor and propeller, said shaft consisting of

two sections the ends of which are adjacent to each other, a relatively thick flexible sleeve telescoped over said adjacent ends, and cotter pins extending through said sleeve and adjacent shaft ends to complete the shaft, said sleeve normally maintaining said shaft ends in slightly spaced relation to each other. 15

In testimony whereof I hereunto affix my signature.

CONRAD R. BUCHET.
